UNITED STATES PATENT OFFICE.

FRANK KRUPICKA, OF FRIEND, NEBRASKA.

FEEDING-TROUGH FOR LIVE STOCK.

1,356,636.

Specification of Letters Patent. Patented Oct. 26, 1920.

Application filed May 10, 1920. Serial No. 380,135.

To all whom it may concern:

Be it known that I, FRANK KRUPICKA, a citizen of the United States, residing at Friend, in the county of Saline and State of Nebraska, have invented certain new and useful Improvements in Feeding-Troughs for Live Stock, of which the following is a specification, reference being had to the accompanying drawings.

10 This invention relates to an improved feed trough for live stock, particularly sheep and the like, and an object of the invention is to provide a feed trough of this kind to be suitably supported in the stock yard in a 15 convenient place and which trough can be moved from one place to another at any time.

While the design and construction at present illustrated and set forth is deemed preferable, it is obvious that as a result of a 20 reduction of the invention to a more practical form for commercial purposes, the invention may be susceptible to changes, and the right to these changes is claimed, provided 25 they are comprehended within the scope of what is claimed.

The invention comprises further features and combination of parts, as will be herein-after set forth, shown in the drawings and 30 claimed.

In the drawings:—

Figure 1 is a perspective view of the improved feed troughs for live stock constructed in accordance with the invention,

35 Fig. 2 is a transverse sectional view through the same showing the trough in upright position in full lines and in an inverted or upturned position in dotted lines,

Fig. 3 is a detail plan view of one corner of 40 one of the troughs, showing the same mounted in a bearing of a lateral ear of one of the arms 7 of one of the brackets.

Referring to the drawings, 1 designates a base which may be a board, plank or any 45 other suitable material and 2 denotes concrete blocks or slabs. These slabs or blocks may, if desired, be constructed upon the ground in the stock yard, in fact partly embedded therein, hence immovable. However, when the concrete blocks or slabs are 50 supported on the wood base it is possible to move the wood base from one place to another in the stock yard.

Secured to the cement blocks or slabs 55 preferably by suitable bolts or the like 4

are brackets 5 which are provided with upturned arms 6 and 7. These arms 6 and 7 are reinforced by the braces 8 which consist of metal straps which are in turn bolted as at 9 to the lower parts of the brackets. 60 Carried by the upper ends of the arms 7 are lateral ears 10 having apertures 11. The upright arms 6 are provided with lateral supporting lugs 12. Suitable feed troughs are provided, and which may be constructed 65 of any suitable material preferably wood or the like, although it is obvious that they may be constructed of metal if so desired, or of any other suitable material. Secured at 13 to the ends of the troughs 14 are angle plates 15 having trunnions 16 which are journaled in the apertures of the lateral lugs on the arm 7. These trunnions are arranged adjacent the rear part of the trough so that when the trough is in an upright position, one side of the trough may 70 rest on the supporting lugs or arms 12 and be held in horizontal planes, whereby live stock can feed from either side.

It is obvious that in the winter, particularly when snowing or raining, the troughs may be inverted or up-turned in order to 75 keep out the snow and the like. Also when it is desired to empty the refuse the troughs may be inverted and then repositioned, in order to receive other feed for the live 80 stock.

Rising upwardly from the ends of the troughs are upright arms 18 which are secured to the ends of the troughs by means 90 of screws or the like 19. Bars 20 are connected to the upper ends of the arms 18 by means of screws 21. These screws 21 and those which secure the upright arms to the troughs can be removed and the bars and 95 the uprights detached and arranged in the troughs when they are put away in storage. The trunnions have apertures 22 which receive cotter pins 23 to prevent detachment of the trunnions from their bearings when 100 the troughs are in use. While it is obvious that the brackets are designed to remain outdoors when the troughs are in storage it is equally understood that they may be detached and placed in storage afterward. 105

The longitudinally extending bars which connect the upright arms of the troughs also act as guards to prevent the heads of the animals from reaching from opposite sides of the trough when in the act of feed- 110

ing. Also the bars in the upright arms of the trough also support the troughs in inverted positions.

It is to be noted that the base 1 which is described as being a board or a plank may be dispensed with, as it is simply illustrated to show some means for supporting the concrete blocks or slabs, for it is obvious that these slabs or blocks are designed to be embedded or set in the ground in the stock yard for the purpose of supporting the brackets.

It is to be noted that the trough can be turned over or inverted in the winter time to keep out the snow and the like so that at all times the trough is clean and when the feed is left in the trough, the trough can be easily inverted to empty the same whereby other feed can be placed therein. Furthermore the trough can be easily and quickly taken apart and the guard bar detached and the trough proper placed away in storage. The cement base may be positioned at various locations in a stock yard so that the trough and its stands can be moved from one base to another. In fact, the cement base may be mounted upon a portable wood base which can be lifted and moved from one place to another and if necessary the wood base can also be placed away out of the weather.

The invention having been set forth, what is claimed as new and useful is:

1. In a feed trough, a base, a pair of U-shaped brackets mounted on the base, certain arms of the brackets having lateral supporting lugs, a feed trough pivotally and operatively supported on other arms of the brackets, whereby the forward part of the trough may rest upon the supporting lugs in an upright position and whereby the trough may be inverted and disposed in an offset direction from over the base, and means constituting a handle and rising upwardly from the trough and adapted to engage the ground when the trough is inverted to support the trough in an inverted position.

2. In a feed trough, a base, a pair of U-shaped brackets mounted on the base, each bracket having long and short upright arms, the short arm of each bracket having a lat-

eral support extending in a direction toward the corresponding support of the short arm of the other bracket, the upper extremities of the longer arms of both brackets having lateral parallel supports extending in planes at right angles to the supports of the short arms, a feed trough pivotally and operatively mounted in bearings of the supports of the longer arms, and adapted, when in an upright normal position to rest on the supports of the short arms.

3. In a feed trough, a base, a pair of U-shaped brackets mounted on the base, each bracket having long and short upright arms, the short arm of each bracket having a lateral support extending in a direction toward the corresponding support of the short arm of the other bracket, the upper extremities of the longer arms of both brackets having lateral parallel supports extending in planes at right angles to the supports of the short arms, a feed trough pivotally and operatively mounted in bearings of the supports of the longer arms, and adapted, when in an upright normal position to rest on the supports of the short arms, said trough being movable pivotally on its connections with the supports of the longer arms to an entirely inverted position, whereby the trough may drain, and a combined handle and trough support raising upwardly from the trough thereby adapted to engage the ground and support the trough when inverted.

4. In a feed trough, a base, a pair of brackets, mounted on the base, a trough pivotally and operatively mounted on certain of the corresponding arms of the brackets, means carried by the other arms of the brackets for supporting the trough in an upright normal position, said trough being tiltable from its normal position to a complete inverted position offset from the base and a U-shaped handle rising upwardly from the ends of the trough and constituting a support adapted to engage the ground when the trough is completely inverted to support the trough in such inverted position.

In testimony whereof I hereunto affix my signature.

FRANK KRUPICKA.
